UNITED STATES PATENT OFFICE.

JOHN J. PUNKE, OF DETROIT, MICHIGAN, ASSIGNOR TO HUPP MOTOR CAR CORPORATION, OF DETROIT, MICHIGAN, A CORPORATION OF MICHIGAN.

DESIGN FOR A DOOR-WINDOW-REGULATOR HANDLE.

Application filed May 21, 1928. Serial No. 26,795. Term of patent 7 years.

To all whom it may concern:

Be it known that I, JOHN J. PUNKE, a citizen of the United States of America, residing at Detroit, in the county of Wayne and State of Michigan, have invented a certain new, original, and ornamental Design for a Door-Window-Regulator Handle, of which the following is a specification, reference being had therein to the accompanying drawing, in which Fig. 1 is a top plan view of my handle. Fig. 2 is a side elevation of my handle. Fig. 3 is a bottom plan view

of the handle shank. Fig. 4 is an enlarged plan view of the knob of my handle. Fig. 5 is an enlarged sectional view taken on the line 5—5 of Fig. 4, and Figs. 6, 7, 8, and 9 respectively are enlarged sectional views taken on the lines 6—6, 7—7, 8—8, and 9—9, respectively, of Figures 1 and 2.

I claim:

The ornamental design for a door window regulator handle, substantially as shown.

JOHN J. PUNKE.
